UNITED STATES PATENT OFFICE.

JOHN HUGH O'NEILL, OF SPRINGFIELD, MISSOURI, AND WARD LEATHERS, OF HAWORTH, NEW JERSEY.

CONTINUOUS-WATER-TUBE FLASH-TYPE STEAM GENERATOR.

Application filed July 24, 1922. Serial No. 576,984.

The object of our invention is to produce a continuous water tube, flash type steam generator of high thermal efficiency and of great reliability and durability. A further object of our invention is to obtain such a generator of the lightest weight per horsepower. A further object of our invention is to make a steam generator of this type which can be built readily in any desired 10 size even up into thousands of horsepower.

Heretofore the coils in continuous water tube, flash type steam generators have been spaced apart and held in place by solid straps or rods of metal which rapidly become oxidized and eaten or burned away due to their exposure to the hot combustion products, hence frequent renewal of such holding means has been necessary. To prevent this deterioration, we so bend the water tubes 15 themselves that they form the spacing and tying and holding elements. To further secure the permanent location of one coil in relation to other coils of the water tubes, where they cross one another they may be 20 welded one to the other by any of the autogenous welding methods such as oxy-acetylene torch or electric welder. Such construction makes it unnecessary to have in 25 the path of the combustion products, metal members which are not cooled and protected 30 by an internal circulation of water or steam, thus adding greatly to the length of life and reliability of the generator, and as all 35 the metal in the path of the combustion products in this arrangement is useful in transferring heat to the water or steam, great saving in weight is accomplished.

On the outside of the coils there may be 40 binding and supporting members of solid metal which are partially out of the path of the combustion products and such members may be cooled by conduction through 45 welds to the tube coils, thus keeping the support members from becoming very hot which prevents such rapid deterioration as would otherwise follow from the high temperatures.

In order to more clearly set forth our 50 invention we herewith describe the design of same and append drawings in which:

Fig. 1 is a diagrammatic, longitudinal cross section of our continuous water tube flash type steam generator.

Fig. 2 is a partial diagrammatic trans- 55 verse cross section of same.

Fig. 3 is a diagrammatic cross section of Fig. 2 on line 3—3.

Fig. 4 is a detail of a special water tube coil protecting the central refractory core of the generator. 60

Fig. 5 is a diagrammatic cross section of Fig. 4 on line 5—5.

Fig. 6 is a sectional view of a protector made of a refractory for this special coil.

In Fig. 1, 1 is a water distributor or 65 meter, which divides the feed water received through pipe 2 from a boiler feed pump not shown and distributes it, in this case, in four equal quantities one to each of the four tubes 3, 4, 5 and 6 which run 70 through the generator as four continuous tubes until united in or joined to the steam header 7 as by the unions 8 and 9, the other two unions not being visible in this view. The tubes 3, 4, 5 and 6 are carried into the 75 path of the combustion products at 10 where the combustion products leave the generator. The tubes are led in an approximately radial direction to the central part of the generator where they are bent through a 80 short arc about a central refractory core 11 and at the same time upward as in a helix about the core 11 until each is on a level above the incoming radial portion, at which point, 12, the four tubes are bent in parallel 85 concentric spirals out to the periphery of the generator coils. At this point, 13, they are again led in, in an approximately radial direction toward the center to a point tangent to the core 11, then the portion of arc in an 90 upward helix is repeated and the spiral pancake also, as is more clearly shown in Figs. 2 and 3. In this way the tubes are bent alternately in a radial direction and then in 95 a spiral pancake, repeated as often as desired, and when welded to each other, as shown at 14, and to the outside support members, as at 15, make a very compact and secure arrangement capable of withstanding the vibration and shock incidental to use on an 100 automotive device. Such radials and pancakes are repeated, with the feed water traveling through the tubes toward the combustion chamber, and in counterflow to the 105 products of combustion, to the point 16 at which point the modification of the counterflow takes place.

The water, which has been heated approxi- 110 mately to the temperature agreeing with the steam pressure carried, is then led by tubes

17 and unions 18 to the second section or zone, located next to the combustion chamber. The tubes 19 continue the radial arrangement which is alternated with the spiral pancakes through which the water and steam is led in a resumed counterflow toward the combustion chamber until at 20 the tubes are bent into a special coil, (shown more fully in Figs. 4, 5 and 6) which is for 10 the purpose of making a relatively solid-water-protected wall over the end of the refractory core 11, thereby protecting the core from the direct blast of the hot gases. At 21 are shown unions by which the four 15 water tubes from coil 20 are joined to the bee-hive shaped combustion chamber which may be formed by bending the four tubes into parallel helices of parallel sides for a part of the beehive and into tapering sides 20 at the upper portion until the water tube wall of the combustion chamber ends at 22. These coils of four parallel water tubes from 19 to 20 and from 21 to 22 form the second 25 section or zone in which the water is evaporated to steam that is nearly dry. These coils are exposed to the combustion products while the combustion takes place, and where the temperature in the gases is maximum, but because of the water and wet steam circulating 30 through them they are protected by the rapid evaporation from being injured by the extremely hot gases, and because of the great temperature difference between the gases and the coils (2500° to 3500° F. in the 35 gases and not to exceed 700° F. in the coils for steam at 3000 pounds pressure) the heat transfer is extremely rapid, probably at the rate of 60 pounds of water or more evaporated per sq. foot of fire heating surface, per hour. This rapid evaporation is necessary 40 in the attainment of light weight in the generator, and it is accomplished without rapid deterioration of the tubes or danger of overheating them, by means of the modified 45 counterflow.

At 23, unions connect tubes 24 which lead the steam to unions 25 which connect to radials 26 from which point radials and spiral pancakes again alternate and through 50 which the steam is again led in resumed counterflow toward the combustion chamber to the point 27 at which the dried and superheated steam is connected to the steam header 7 by the unions 8 and 9 and two more unions 55 not shown, in this view.

From point 26 to point 27 is the third section or zone of the modified counterflow. In this section the steam is dried and superheated in tubes exposed to the combustion 60 products cooled to approximately 1500° to 1800° F. at the point 27 by having passed over the tubes from 20 to 19. Because of the small temperature difference (400° to 500° F.) between the combustion products 65 and the tubes and contained steam, consider-

able variation in the flow of steam may take place without damage to the tubes from overheating.

At 28 is the pipe through which is pumped or forced by other controllable means, the oil fuel from a source not shown. The oil is vaporized in the tube coil 29 which forms a portion of the combustion chamber wall and may be exposed to the direct heat of the combustion, as shown, or may have some coils of the steam tubes 22 between the coil 29 and the source of heat. From the coil 29 the oil vapor is delivered at 30 to the annular chamber 31 from which it issues through the small tubes 32 and the holes 33 at right angles to the air which enters the combustion chamber through the round port 34 formed by the annular chamber 31. In this way a very intimate mixture is made of the oil fuel vapor and the combustion supporting air. At 35 air for supporting combustion is supplied from a blower and measuring device not shown. The waste combustion products which have passed over the water coils and the incoming air flow in opposite directions through alternate channels formed of suitable metal such as aluminium, so that the heat from the waste gases is transferred through the metal walls to the incoming air, warming the air to approximately 250° F. while cooling the gases to 300° to 350° F. The incoming air from the distributing chambers 36 passes as shown by the dotted arrow 37 to the connecting elbows 38 and through them into the annular space 39 and flows upward around the steam generator between the inside heat insulating wall 40 and the outside heat insulating casing 41. The air is further heated by the heat escaping from wall 40, so that it enters port 34 at about 400° F. Because of this preheating of the air and because the oil fuel is in a hot vaporized state, the combustion is very vigorous and the resulting temperature is about 3500° F. where an approximately 10% 105 excess of air is supplied. The products of combustion pass downward from the combustion chamber 42 flowing between the tubes of the pancakes and radials from 20 to 19 of the second section, from 27 to 26 of the third section, from 16 to 10 of the first section, then, as shown by the solid arrows 43, through channels alternate to the incoming air channels to collector 44 and exhaust flue 45. The incoming air and exhaust gases 110 are guided in counterflow by the directing partitions 46 which are the same in each channel. At 47 is shown a binding and supporting T or angle iron which may be welded on the coils continuously from bottom to top, or in lengths to correspond with the sections, so that the sections can be assembled 115 separately and then joined into the complete generator as is shown by the joint detail more clearly in Fig. 7.

At 48 the inner sheet of wall 40 is shown. This sheet steel member is welded to the support members 47 and makes with the outside sheet 49 an airtight casing around the generator. The space between inside sheet 48 and outside sheet 49 of wall 40 is filled with suitable heat insulation such as magnesia or asbestos. At 50 is shown a solid refractory such as refractory brick, which may be placed between the tube coils and the sheet 48 where the flow of combustion products of high temperature past the surface would make it advisable to do so. Joints 51 are provided in the outer shell 41 and the inner wall 40 wherever desired for convenience in assembly of the generator. At 52 is shown an opening with a screw plug which may be used to start the combustion by any desired means such as insertion of a torch flame or 20 inflamed oil saturated waste or permanent electric spark gap and gasoline and air supply.

In Fig. 1 was illustrated a steam generator suitable for standing vertically with the combustion chamber at the top, wherein the water would always be trapped or drained to the bottom of each section, with a minimum of tendency to flow toward the steam outlet. It could also be used horizontally, in which case each coil would form a trap. This form of generator is suitable for large and quite steady output.

In Fig. 2, 49 is the outer sheet of wall 40, and 48 the inner sheet. 48 is joined to support member 47 by welding. 53 and 53 are hand hole covers which may be provided for conveniently closing or opening the unions 8 as on header 7 or on other joints as union 18 on radial 19. Fig. 2 is to more clearly show how the radials are carried in from the periphery as at 54 and pass around the core 11 as at 55 and then are bent spirally outward as at 56 and out through sheet 48 as at 57 to accommodate a union or the tube may be 45 bent inwardly again as a radial as at 58.

Fig. 3 illustrates the change of level of the radial 54 in passing into the spiral at 55 and 56 and in passing from pancake to radial as at 58.

Figs. 4 and 5 illustrate more clearly the special coil at 20 wherein the four tubes are brought repeatedly over the central core and are welded together in the center as shown at 59. This is useful as it is difficult to obtain a refractory for the core 11 which would endure the hot blast at 3500° F. without some water cooled protection.

Fig. 6 shows a refractory cap 60 which may be held by metal spikes welded to 59 and used as a protection to the tubes against the hot blast of the combustion products. This protector cap may or may not be used, depending on the size and service of the generator, and may be of any size or shape and also function as a hot "surface combustion" member, which is partially cooled by contact with the tubes of coil 20, which partial cooling will enable the refractory to stand up under intense heat of the gases.

Naturally there are many combinations possible of the improvements described in our steam generator, and all these various combinations fall within the spirit of our invention.

We claim:

In a flash type steam generator, a plurality of continuous water and steam conduits, said conduits being arranged in parallel relation in alternate layers of spiral coils and radially disposed portions of said conduits, said conduits being adapted to form supports, spacers and tying members in one layer for the other layer, said conduits in one layer crossing said conduits in the next adjoining layer, said conduits being automatically welded together at said crossings.
